UNITED STATES PATENT OFFICE.

MARC RESEK, OF CLEVELAND HEIGHTS, OHIO, ASSIGNOR TO PERFECTION STOVE COMPANY, OF CLEVELAND, OHIO, A CORPORATION OF OHIO.

OIL STOVE.

Application filed January 12, 1925. Serial No. 1,819.

This invention relates to oil stoves, and its objects are to provide a very simple, compact and inexpensive oil stove of the stand type that may be used for cooking, the same being of the class used for camping, picnicking and other purposes where a light, cheap and readily portable stove is desired; and to provide a novel construction for a stove of the foregoing nature which, if desired, may be made for convenient assembling by the dealer or user without the use of tools, thus enabling the structure to be packed in disassembled condition in compact form for storage and shipment.

The foregoing objects, with others herein-after appearing, are attained in the embodiments of the invention illustrated in the accompanying drawings wherein Fig. 1 is a central vertical section through the stove; Fig. 2 is a horizontal section on the line 2—2 of Fig. 1; Fig. 3 is a detail of one of the legs; Fig. 4 is a side elevation of a modified form of the invention, parts being shown in section to disclose certain structural details; and Fig. 5 is an inside elevational view of one of the legs of the latter form of the invention.

A suitable number of legs 1, three being at present preferred, connect top and bottom members or rings 2 and 3, respectively. The legs are of channel formation, and the webs of the channels are spot welded or otherwise connected at top and bottom to the respective rings 2 and 3, said webs being beaded throughout the greater portion of the distance between said rings, as shown at 4. The top and bottom rings have flanges 5 and 6, respectively, against which the ends of the legs engage. The foregoing parts are all preferably made from sheet metal, the rings 2 and 3 being rolled from strips and held in annular form by their wider flanges being extended at one end beyond their narrower flanges to provide tongues 2^a and 3^a, respectively, that are spot welded or otherwise secured to the opposite ends of said wider flanges. Resting within the top ring 2 is a grid 6^a for the support of a cooking utensil or other object to be heated.

A suitable distance upwardly from their lower ends, the side flanges of the legs 1 are widened, as shown at 7, and notched, as shown at 8 (Fig. 3) for the reception of a peripheral bead 10 that surrounds an annular oil reservoir 11 within the central open-

ing of which is disposed an oil burner 12. This burner is of the tubular type and is comprised of inner and outer tubes 13 and 14 which are connected together at their lower ends by a wall 15, thereby to enclose 60 an oil space 16 within which a cylindrical wick 17 is adapted to be raised and lowered by wick adjusting means designated 18.

An air controlling member or flame spreader 20 is supported within the upper end of the burner by a member 21, and a collar 22 surrounds the burner and has its upper end in spaced relation to the flange 23 of the air controlling member or flame spreader 20. These are the details of a 70 well known type of oil burner and they constitute no part of my present invention. The collar 22 is connected to and spaced from the upper end of the outer burner tube 14 by brackets 24, and fins 25 connect the 75 burner to the reservoir 11. Communication is established between the reservoir and the lower portion of the oil space 16 through a pipe 26. Surrounding the upper end of the burner and shown as supported thereabove 80 by the lower end of the collar 22 is the usual burner drum or flue 27.

When it is desired to construct the stove in such manner that it may be packed or shipped in disassembled condition for the 85 sake of compactness and convenience of handling, the tops and bottoms of the legs 1 may be made to have an interlocking connection with the rings 2 and 3, and such a connection is illustrated in Fig. 4 where the 90 webs of the legs are shown as having tongues 30 struck from their upper and lower ends for engagement through slots in the top and bottom rings 2 and 3 the tongues being preferably turned over on the outer sides of the 95 rings so as to better secure the parts together.

In the present structure I have shown a further change which avoids having to form the side flanges of the legs 1 with the enlargements 7. In the present instance short channel members 32 are fitted within the legs 1 and prongs 33 which project from the ends of the channel members are inserted through slots in the webs of the legs and turned over therebeyond. The side flanges 34 of the 105 channel members taper inwardly from their opposite ends to about the center where they are provided with notches 35 for the reception of the bead 10 of the reservoir 11.

It may be explained that the legs 1 are 110

sufficiently resilient to permit their being bowed outwardly and thus disengaged from the bead 10 of the reservoir 11, permitting the reservoir to be tilted and removed from the frame structure. This is an advantage in cleaning the burner and especially in draining the reservoir. The cam shape given the flanges of the legs 1 in the vicinity of the notches 8, and the flanges 34 of the channel members 32 in the region of the notches 35, enable the reservoir to be easily inserted, as by engaging the bead 10, adjacent one side of the reservoir, in the notches of two of the legs, and then pressing the reservoir to a horizontal position during which it will cause a slight spreading of the legs until the bead 10 registers with the notches of the remaining leg upon the occurrence of which the legs will spring inwardly and securely 20 lock the reservoir in place. In the form of the invention shown in Fig. 4, the presence of the reservoir in the frame structure insures against inward movement of the legs and consequently against any possibility of the ends of the legs becoming disengaged from the top and bottom rings 2 and 3.

Having thus described my invention, what I claim is:—

- 30 1. A stove comprising a top member, a bottom member, legs having their upper and lower ends detachably connected to said members, and a burner structure supported solely by and between the legs and detachably connected thereto, said burner structure serving to maintain the legs in such position as to prevent their disconnection from the top and bottom members.
- 35 2. A stove structure comprising a top ring, a bottom ring adapted to rest on a supporting surface, resilient legs having their upper and lower ends disposed inside and bearing on said rings, the legs having in-

wardly opening notches spaced a suitable distance above the bottom ring, and a burner structure incorporating a reservoir 45 having a peripheral bead that is engaged within the notches of the legs.

3. A stove structure comprising a top ring, a bottom ring, resilient legs having their upper and lower ends engaged within 50 and interlocked with said rings, the legs having inwardly opening notches spaced a suitable distance above the bottom ring, and a burner structure incorporating a reservoir having a peripheral bead that is engaged 55 within the notches of the legs, the burner structure serving to maintain the legs under tension.

4. A stove structure comprising a top ring, a bottom ring, legs spacing apart and connecting together said rings, the legs being of channel formation and having notches in their side flanges that are spaced a suitable distance above the bottom ring, the side flanges gradually flaring inwardly 65 to where they are interrupted by said notches, and a burner structure incorporating a reservoir having a peripheral bead that is adapted to be engaged within said notches.

5. A stove comprising a top ring, a bottom 70 ring, legs spacing apart and connecting together said rings, the ends of the legs having interlocking connection with the rings, channel members secured to the legs, the side flanges of said members having inwardly 75 opening notches, the inner edges of said flanges receding gradually from the notches, and a burner structure incorporating a reservoir having a peripheral flange that is engaged within said notches.

In testimony whereof, I hereunto affix my signature.

MARC RESEK.
